[57] CLAIM

The ornamental design for the cabinet for holding a plurality of cathode ray tube computer terminals, as shown and described.

DESCRIPTION

FIG. 1 is a reduced front perspective view of a cabinet for holding a plurality of cathode ray tube computer terminals showing our new design;

FIG. 2 is a side elevational view thereof;

FIG. 3 is a rear elevational view thereof;

FIG. 4 is a reduced front perspective view thereof as shown in FIG. 1 with the keyboard supports extended;

FIG. 5 is a front elevational view thereof;

FIG. 6 is a top plan view thereof; and,

FIG. 7 is a bottom plan view thereof.

FIG. I.

FIG. 2.

FIG. 3.

FIG. 4.

FIG. 5.

FIG. 6.

FIG. 7.
